Letter 23, 1836 9340X 44
Stephen Ho Long, Jr. Col. of the U.S. Topographical Eng'rs
Letters Patent

The Schedule referred to in these Letters Patent, making part of the same, containing a description in the words of the said Stephen Ho Long of his improvement in the construction of wooden Bridges.

Specifications of various improvements in the construction of wooden or frame Bridges invented by S. Ho Long Jr. Col. of the U.S. Topo. Engineers. - The object of these improvements is to produce and insure lateral stiffness or inflexibility in wooden or frame bridges which object is effected by means of a plan or system of bracing, applied either to the upper or the lower strings of the Bridge or to both, should it be deemed advisable, which plan or system I shall designate by the name of lattice bracing and which is of the following description.

The lattice bracing consists of timbers of suitable dimensions about 3 by 9 to 12 inches transversely and of any appropriate length applied diagonally either above or below the strings of the Bridge, an application to the upper strings being deemed preferable in ordinary cases and is confined to the strings by bolts, spikes or treenails or by any or all of these modes of fastening combined; the bolts being placed through the brace timbers at their intersections and through or into the strings at the places where the former are attached to the latter. - The arrangement of the brace timbers is such as to exhibit two sets of braces one diagonal to the other; the timbers in each set being parallel to each other or nearly so. - The arrangement also provides that one set of the braces shall rest or recline upon the other in such a manner that the ends of the braces of one set shall rest or recline upon the other in such a manner that the ends of the braces of one set shall rest immediately upon the ends of the other set. - In addition to the attachment of the strings in the manner above specified, the brace timbers of each set are confined to those of the other set at every intersection by similar fastenings. - Moreover - the lattice bracing may be more strongly bonded to the strings

and rendered more efficient on other respects by means of binders or strainers of suitable dimensions between which and the strings the loose timbers interwine and which are confined to the strings by braces by means of the same bolts, treenails or spikes, sufficiently prolonged for this purpose that confine the bracing to the strings. The binders or ribands are to be applied to the Traction Bridge in such a manner as to rest between the heads or ends of the posts of the truss frames, the binders being notched in a manner forming an adjustment as represented in the accompanying drawings of the model herewith transmitted.

In the use and application of the Lattice Bracing to the upper strings of a Bridge the necessity of beams to confine the strings together and to afford the diagonal support for roofing is entirely obviated a beam however is required in case of the travel over each pier and abutment to serve as a bond for the lateral bracing and more especially to afford the means of introducing transverse braces to better advantage.

Explanation of the Drawings.

Fig 1 represents a side view of the bridge or rather one of its truss frames, and shows the manner in which the ends of the Lattice braces are presented as also the position of one of the Binders or ribands.

Fig. 2. exhibits a plan or direct Bird's eye view of the Lattice-bracing and its connections with the truss frames of a Bridge.

Fig. 3 represents an end view of the Bridge, showing the position of one of the piers or abutments, beams, the stay braces, & alterations - of the upper set of the lateral braces.

(a) the ends of the same B. the lower set of the lateral braces

(b) the ends of the same C. The Binders, strainers or ribands

D. the beams over the abutments of Piers with their stay braces -

E. The Poles for supporting the Bridge F. Stay-braces for bracing the bridge laterally.

The improvements herewith in the foregoing specification

and claimed as new and useful, consist in the application and use of lattice work in the manner and of the description herein explained for the purpose of imparting the requisite lateral stiffness to wooden bridges, in a manner more simple, economical and efficient, than the means heretofore employed for that purpose, it being understood that lateral and horizontal stiffness in contradistinction from vertical and transverse or flexibility is the object of this invention.
